CLAIM

The ornamental design for a cone for a kit for the analysis of platelet function and body fluid specimens, as shown and described.

DESCRIPTION

FIG. 1 is a perspective view of cone for a kit for the analysis of platelet function and body fluid specimens, showing our new design;

FIG. 2 is a front view thereof;

FIG. 3 is a top plan view thereof;

FIG. 4 is a bottom plan view thereof;

FIG. 5 is a left side elevational view thereof; and,

FIG. 6 is a right side elevational view thereof.
